UNITED STATES PATENT OFFICE.

JOHN GREEN HAMLEY, OF LONDON, ENGLAND.

TOY OR AMUSEMENT DEVICE.

1,028,068.

Specification of Letters Patent. Patented May 28, 1912.

Application filed March 7, 1911. Serial No. 612,771.

To all whom it may concern:

Be it known that I, JOHN GREEN HAMLEY, a subject of the King of Great Britain, residing at 86 High Holborn, in the county of 5 London, England, toy merchant, have invented certain new and useful Improvements in Toys or Amusement Devices, of which the following is a specification, reference being had to the drawings hereunto annexed 10 and to the figures and reference-numerals marked thereon—that is to say:

The invention relates to improvements in toys or amusement devices.

The object of the invention is to obtain a 15 novel device adapted to fit upon and hold to the hand of the operator in a manner to leave the fingers free for actuating operative parts of the device, and having lips or mouth members constructed with internal 20 pockets or sockets for the finger and thumb and rendered not only relatively movable, but with inherent flexibility, so that the shape of said members as well as their relative positions may be changed through a 25 wide range; also to provide eyes with operating connections within convenient reach of the other hand, so that they may be moved in various ways; the whole being designed to permit the development of amusing 30 effects.

The device may represent the head of a human being or that of an animal, such for example as an ape, fish, bird or reptile either having an actual or correct form or a grotesque appearance.

For convenience the invention will be described as applied to a toy representing the head of an ape. For this purpose the head or part of it is formed as a kind of bag 40 constructed of felt, cloth or other suitable material or combination of materials and all except the face is covered with hair or the like and the face is formed wholly or partially flexible and is colored to imitate the 45 skin of the animal. The lips or jaws are preferably flexible and those and the inside of the mouth are of a different but appropriate color to the rest of the face, preferably red, and the lips and jaws are formed 50 separable or constructed so as to open and close. The neck, which is fur covered, has an opening to receive the hand of the operator which it more or less incloses and each lip or jaw is composed of or provided with 55 a pocket, the pocket of the lower lip being

small and the operator inserts his thumb into the small pocket of the lower lip or jaw and his fingers into the larger pocket of the upper lip or jaw and by manipulating or distorting said lips, and the entire face when 60 it is flexible, some grotesque and extraordinary effects may be produced. The eyes are preferably made revoluble and carried by rods which converge and protrude and meet at the back of the head so that the lips may 65 be manipulated by one hand and the eyes by the other.

In the accompanying drawings:—Figure 1 is a side elevation of a toy, constructed according to the present invention, and by 70 way of example made to represent the head of an ape. Fig. 2 is a similar view partly in section and showing by dotted lines the hand of the operator in position in the bag like lower part of the device, the lips or jaws 75 being shown closed or nearly so. Fig. 3 is a similar view showing the lips or jaws open. Fig. 4 is a similar view to Fig. 1 illustrating a means of manipulating the eyes. Fig. 5 is a horizontal section taken on 80 the line A—A of Fig. 4 and Fig. 6 represents one way in which the operator may manipulate the device.

In the several figures like parts are indicated by similar reference numerals and 85 Fig. 6 is drawn to a reduced scale with respect to the other figures of the drawings.

Referring to Figs. 1 to 3, 1 represents the head of the device, appropriate parts of which are covered with hair as shown, and 90 the upper part of the head is or may be filled in so as to be more or less rigid, or it or the face may be wholly flexible.

In the present example the lower part of the head including the neck and the lips or 95 jaws is made flexible as a kind of bag and the neck is formed with an opening to receive the hand 5 of the operator as shown at Figs. 2 and 3, and is provided with an elastic band 2 to encircle and grip the wrist of 100 the operator and thus assist to retain the device in position; or any other suitable device than an elastic band may be employed for that purpose.

The lips or jaws 3, 4, are each composed 105 of or provided with a pocket, the pocket of the lower lip or jaw 4 being smaller than that of the upper lip or jaw and adapted to receive and fit the thumb of the operator while the pocket 3 of the upper lip or jaw 110

is formed of suitable dimensions to receive all the fingers of the hand as shown at Figs. 2 and 3.

When the device is in use the operator 5 inserts his hand 5 into the bag like lower part of the head 1 with the thumb and fingers arranged in the manner above indicated and the elastic band encircling his wrist and by manipulating the lips or jaws 10 he is able to produce various grotesque or other expressions of the face and cause the lips or jaws to open and shut as if in the act of eating or biting.

In the example given at Figs. 4 to 6 a 15 means of manipulating the eyes is illustrated. In this case the eyes 6 are carried by converging rods 7 revolvably mounted in the head and at the opposite ends made to 20 protrude at the back of the head and meet or nearly meet so that both rods 7 may be manipulated at that point by the thumb and fingers of the hand that is not manipulating the lips or jaws, and said protruding ends may be provided with spherical devices or 25 beads upon the ends thereof. The manipulation of the eyes 6 is effected by rolling the protruding parts 8 of the rods 7 between the fingers and thumb or otherwise.

The method of using this device in this 30 manner is illustrated at Fig. 6 from which it will be seen that the right hand of the operator is inserted in the bag like device and holds the head so that it looks over the left upper arm while the left arm is bent 35 around so that the left hand is in a position to manipulate the protruding parts 8 of the rods 7 of the eyes 6. In this manner a very realistic and grotesque effect can be obtained which will afford infinite amusement both to children and adults.

In some cases I may elect to attach an appropriate body to the neck of the head 1 while still leaving an opening for the insertion of the hand 5.

Although the invention is hereinbefore 45 illustrated as applied to a device representing the head of an ape it will be obvious that it may be made to represent the head of a human being or animal such as a fish, 50 bird or reptile and may be given in its normal state the natural appearance thereof or may be given a mythical or grotesque ap-

pearance, the device being of course appropriately covered with hair, scales or feathers as the case may be.

55

Having now particularly described and ascertained the nature of the said invention and in what manner the same is to be performed I declare that what I claim is:

1. A toy or amusement device constructed 60 in imitation of an animate object and having lip simulating members flexible as well as relatively movable and provided with internal pockets, a wall of each pocket providing the surface for a lip whereby the 65 thumb and finger of a hand may be introduced in position to fill out and give shape to the mouth members, and the mouth of the device may be modified in shape as well as opened and closed.

70

2. A toy or amusement device constructed 75 in imitation of an animate object and having lip-simulating members flexible as well as relatively movable and provided with internal pockets to receive the thumb and 80 finger of a hand, the surface of each lip being provided by one wall of a pocket whereby the thumb and finger are in position to fill out and give shape to the mouth members, so that the mouth of the device may 85 be modified in appearance as well as opened and closed; said device being constructed to grip upon and hold to the hand in rear and independently of the mouth members.

70

3. A toy or amusement device constructed 85 in simulation of the head of an animate object and having eyes with rigid rods carrying said eyes, mounted to rotate in and extending through the head and constructed at their rear ends for manipulation in rotary direction.

90

4. A toy or amusement device constructed 95 in simulation of the head of an animate object and having eyes with rods upon which said eyes are mounted extending through the head and constructed at their rear ends for manipulation in rotary direction, said rods being converged at their rear ends to bring them together for simultaneous rotary manipulation.

JOHN GREEN HAMLEY.
